UNITED STATES PATENT OFFICE.

EDWIN C. WASHBURN, OF ENGLEWOOD, NEW JERSEY.

CAR-AXLE CONSTRUCTION.

1,285,504.

Specification of Letters Patent. Patented Nov. 19, 1918.

Application filed April 25, 1918. Serial No. 230,623.

To all whom it may concern:

Be it known that I, EDWIN C. WASHBURN, a citizen of the United States, and a resident of Englewood, in the county of Bergen and State of New Jersey, have invented an Improvement in Car-Axle Construction, of which the following is a specification.

This invention relates to car axle construction. One of the objects thereof is to provide a construction of the above type which shall be strong and dependable in use. Another object is to provide a construction of the above nature which shall possess excellent wearing qualities without high cost. Another object is to provide a simple and practical art whereby the life of car axles may be materially increased. Another object is to provide an art of the above nature whereby car axles may be made better to resist wear. Other objects will be in part obvious and in part pointed out hereinafter.

The invention accordingly consists in the features of construction, arrangement of parts and in the several steps and relation of steps, all as will be herein illustratively described and set forth in the appended claims.

In the accompanying drawings, in which is shown one or more of various possible embodiments of the several mechanical features of this invention,

Figure 1 is a longitudinal view of a portion of a car axle with a portion of a wheel partially cut away in central longitudinal section; and

Fig. 2 is a similar view of similar parts. Similar reference characters refer to similar parts throughout both views of the drawing.

Referring now to Fig. 1 of the drawings, there is shown one end portion of a car axle 1 which terminates in an annular portion 2. The axle is provided with an extension or journal portion 3 which is preferably made of a superior grade of metal better adapted to resist wear than the body of the axle.

The extension or stub 3 is provided with a boss 4 which tightly fits within the annular portion 2 and the end of which rests evenly against the wall 5 formed by the body of the axle 1. There is formed about this boss a shoulder 6 which meets the end of the annular portion 2 and brings the diameter

of the stub or extension up to that of the main axle portion 2 fitting tightly against the latter.

The above parts are preferably assembled and secured in position as hereinafter later explained.

With the stub and main axle assembled, the car wheel 7 is forced over the joint as by hydraulic pressure and tightly embraces the same, aiding in holding the parts in place.

In the apparatus shown in Fig. 2, of the drawings, there is provided a hollow tubular axle 8 which may be formed of cast steel and is preferably of larger diameter than the usual solid axle, thus giving far greater strength and stiffness with a given amount of metal.

The outer end of the axle is recessed or chambered as at 9, and tightly fitted therein is a stub or extension 10 which may be formed of metal better adapted to resist wear than the body of the axle. This extension rests at its inner end against the shoulder 11 formed by the body of the axle and with the parts assembled, the car wheel 12 is forced over the joint, thus aiding in the strength of the connection.

In the use of car axles, the journal portion or that part projecting outwardly from the wheel, which, through the bearing and axle box supports the weight of the car, is subjected to wear and in time becomes worn to such an extent that the continued use of the axle in such condition is inexpedient. To meet this condition and avoid waste, I have devised an art or method which may be illustratively described as follows:

The wheel is withdrawn from the axle and the latter cut off and bored out to provide an end construction similar to that of the part 1, shown in Fig. 1 of the drawing. An extension or stub is thereupon shaped substantially like the part 3 of Fig. 1 of the drawing, the boss, however, being of a slightly larger diameter than the opening or chamber into which it is to fit. The axle is then heated to expand its annular end portion, and the parts 1 and 3 assembled, whereupon the main axle is permitted to cool and shrink about the boss formed on the stub. This forms a rigid connection between the parts which is readily made.

Other methods of union however, may be employed, although there are certain advantages in that above described.

With the parts connected, the wheel 7 is forced as by hydraulic pressure over the joint into substantially the position indicated in Fig. 1 of the drawing, a shoulder 13 being preferably provided to limit the inward movement of the wheel.

- 10 It will thus be seen that by an art such as that above described, the body of the axle is retained instead of being scrapped, and that if in time the stub portion 3 became worn, notwithstanding its superior wearing qualities, it could again be readily replaced, resulting in a marked economy of metal.

Also in the resultant structure, due to the interlocking relation of the parts, there is provided an axle which is strong and well adapted to resist the conditions of practical use. Furthermore, without material increase in cost, its wearing qualities are greatly increased. As various changes might be made in the above construction and as variations might be made in the method of carrying on the above art, all without departing from the essence of this invention, it is to be understood that all matter herein described or shown in the accompanying drawing is to be interpreted as illustrative and not in a limiting sense.

I claim as my invention:

1. In car axle construction, in combination, a wheel hub, a main axle portion and a journal portion, said portions having an interfitting joint one with another wholly within said hub and each portion being solid as it enters said hub.

2. In car axle construction, in combination, a solid main axle portion provided with a recess at its end and a journal portion fitted within said recess said journal portion abutting against said axle portion to limit its longitudinal movement toward the same.

3. In car axle construction, in combination, a solid journal portion, a main axle portion embracing said journal portion, and a wheel hub shaped to grip directly both said journal portion and said axle portion.

4. In car axle construction, in combination, a main axle portion and a journal portion, one of said parts being provided with a longitudinal recess and the other of said parts fitting said recess and resting against a bottom wall thereof.

5. In car axle construction, in combination, a main axle portion, a journal portion, said main axle portion being provided at its end with an annular extension and said journal portion having formed thereon, a projecting part fitting within said extension, and a shoulder resting against the end of said extension.

6. In car axle construction, in combination, a two-part axle, the external diameter

of the parts at their junction being equal, and the outer part having a portion of reduced diameter which enters and fits the side and bottom walls of a recess formed in the inner part and which is surrounded by a shoulder fitting the end of said inner part.

7. In car axle construction, in combination, a main axle portion and a journal portion, one of said parts being provided with a longitudinal recess and the other of said parts fitting said recess and resting against a bottom wall thereof, and a wheel embracing the joint between said portions.

8. In car axle construction, in combination, a main axle portion and a journal portion, one of said parts being provided with a longitudinal recess and the other of said parts fitting said recess and resting against a bottom wall thereof, the journal portion of said axle being formed of a type of metal better adapted to resist wear than the main portion thereof.

9. In car axle construction, in combination, a solid axle portion provided with a substantially cylindrical recess at its end, a journal portion fitted within said recess and shaped to limit its longitudinal movement.

10. In car axle construction, in combination, a wheel hub, a main axle portion provided with a recess, a journal portion fitted within said recess and shaped to limit its longitudinal movement, and a wheel hub embracing said joint between said portions, each of said portions being solid as it enters said hub.

11. In car axle construction, in combination, a wheel hub, a main axle portion provided with a cylindrical recess, a journal portion fitted within said recess and shaped to limit its longitudinal movement, and a wheel hub embracing said joint between said portions, each of said portions being solid as it enters said hub and each of said portions being gripped directly by said hub.

12. The art of renewing a worn axle which consists in cutting off its journal portion forming a recess in the end of the axle portion, bringing a new journal portion into said recess in tightly gripped relation thereto and forcing a wheel over the joint between said main axle portion and said new journal portion.

13. The art which consists in forming at the outer end of a main axle a longitudinal recess, heating the portion within which said recess is formed, inserting therein a relatively cool journal portion, permitting the first portion to shrink about the same, and forcing a car wheel tightly over the joint between said portions.

14. The art of renewing a worn axle which consists in cutting off the journal portion thereof forming a cylindrical recess in the end of the main portion, bringing a new journal portion into said recess in tightly

gripped relation thereto and abutting against the same in a longitudinal direction and forcing a wheel over the joint between said main axle portion and said journal portion.

5 15. The art which comprises forming a socket in the end of a main axle, providing a journal portion of a metal adapted to resist wear, fitting the same to substantially

fill said socket and forcing a car wheel tightly over said portions into direct engagement with the exterior of said socket and with a part of said journal portion. 10

In testimony whereof I have signed my name to this specification this 17th day of April, 1918.

EDWIN C. WASHBURN.
